TYPE LINE COMPOSING AND PRINTING
MACHINE USING CIRCULATING PATRICESPaul Marti, Winterthur, Switzerland, assignor to
firm Schweiz. Lokomotiv-und Maschinenfab-
rik, Winterthur, SwitzerlandApplication August 8, 1933, Serial No. 684,245
In Germany August 16, 1932

3 Claims. (Cl. 101—93)

This invention relates to type line composing and printing machines using circulating patrices which are taken out of magazines, set in lines, inked, printed and restored into the magazines again. In such line setting and printing machines the set line is printed on one side of a transparent sheet stretched over a printing cylinder. This method is, however, unsatisfactory, as a proper covering of the printed types, is not obtainable due to the particular nature of the surface of the printing sheet, and furthermore such printed pattern sheets are only applicable as patterns for intaglio printing plates, whereas, for the production of plates for offset printing only pattern sheets that are printed on the backside (positives) are used.

According to the present invention, the transparent printing on both sides is rendered possible with a line setting and printing press by means of a printing mechanism wherein the inscription image of the inked lines is taken up by a resilient base, for example, rubber and then printed therefrom together with the type lines after the interposition of the transparent sheet thereon.

In machines of the previously-mentioned kind, this permits of transparent printing with good covering of the printed type, as the resilient base permits of easy printing (impression) but which, however, is sufficient for covering the type. These transparent sheets may thereby be used as reproduction copies for offset as well as for intaglio printing.

The shifting of the printed sheet and the base is effected by means usual in the printing art by means of a line shift device.

The sheet is interposed in the printing position preferably on a carriage running on rollers.

In the accompanying drawings a constructional form of the invention is illustrated by way of example only, in which

Fig. 1 shows a front elevation of the printing device of the machine with the parts in inoperative position,

Fig. 2 shows a side elevation of the same with the parts in inoperative position and the driving mechanism omitted.

Fig. 3 is a view of the feed device for the paper slide,

Fig. 4 is a view of the feed means for the printing cylinder inclusive of the printing form, and

Fig. 5 shows a side elevation of the machine with the parts in printing position inclusive of the various driving members.

In the magazines 1, which are vertically directed, the patrices 2 are stored.

The key-board 3 is connected in a usual manner with the magazines 1. The collecting device 4 connects the magazines 1 with the collecting channel 5 which serves as a guide for the patrices 2 on their way to the printing device. A spacing

device or justifier 6 of conventional construction secures the collected patrices in their relative positions. A cylinder 9, which carries the resilient printing form 10, is mounted for rotation in the printing carriage 21 and adapted to be displaced in unison with said carriage in the vertical direction by means of the guide 22 for the printing carriage.

A tension bar 24 attached to the printing carriage 21 by means of a pin 23 is connected at its other end with a control lever 29, which is provided with a guide roller 26, by means of a pivot pin 25, said lever in turn being pivoted to the shield 28 of the machine frame at 27. The roller 26 runs on a cam disc 31 carried on the main drive shaft 30, thus imparting to the printing carriage 21 a downward motion against the action of a compression spring 32.

Behind the printing carriage 21 an inking device 7 of a usual construction is arranged which supplies two inking rollers 8 with color. A cam disc 33 actuates a two-armed lever 35 mounted on a carrier 34 and provided with a guide roller 36 and a pivot pin 37 to which the pusher arm 38 is connected the other end of which carries the inking rollers 8 in rotatable manner. Two upwardly bowed rails 20 act as a guide for the inking rollers 8 on their travel across the patrices 2. A tensioning device 19, as usually combined with printing cylinders, permits of spreading the printing form 10 on the cylinder 9 in a stretched condition. On the pivot 39 of the cylinder 9 a feed lever 17 carrying a pawl 40 is rockably arranged, the other end of this lever sliding in a guide loop 41, whereas the pawl 40 engages in a ratchet wheel 42.

To a bracket 43 two track rails 44 are secured, on which a paper slide 15 runs by means of rollers 14. The drive of the slide 15 is effected by means of an intervening pin 45 by a lever 16, the other end of which is mounted on a bolt 46 and which is actuated by a control arm 48 through the intermediary of a link 47. A guide roller 49 arranged on the outer end of this link cooperates with a cam disc 50 on the main drive shaft 30. A tension spring 51 attached to the lever 16 urges the latter on the cam disc 50. In the paper slide 15 a paper carrier frame 12 is displaceably arranged. 13 designates a transparent sheet which in a usual manner is secured by clamping rollers 11 to the frame 12 a toothed portion of which cooperates with a gear wheel 52 which is connected to a ratchet wheel 18 by a shaft 53 (Fig. 3). A pawl 54 carried by a two armed spring pressed lever 56 cooperates with the ratchet wheel 18 and is controlled by a stop 55 adjustably arranged in a support 57 on the bracket 43.

The operation of the above-described arrangement is as follows:

The patrices 2 contained in the magazine 1 are

released by depressing the keys 3 and thus caused to pass through the collecting device 4 into the collecting channel 5 through which they are conveyed as a set line under the cylinder 9 by the spacing or justifier device 6. Thereupon, the cam disc 33 operates the two-armed lever 35, so that by means of the pusher arm 38 the two inking rollers 8 are moved away from the inking device along the guide rails 20 and across the patrices 2 united into a set line for inking in the same.

The inking rollers 8 remain at rest in the position shown in chain dotted lines in Fig. 5, while the cam disc 31 moves the control lever 29 and thus the tension bar 24 so as to displace the printing carriage 21 downwardly in its guide 22 until the printing form 10 overlying the cylinder 9 contacts with the inked in set line of patrices.

When the cam disc 31 rides off the roller 26, the spring 32 forces the printing carriage upwards some distance, whereupon the lever 35 returns together with the pusher arm 38 and the inking rollers 8 into inoperative position in such manner that the inking rollers 8, during their retracting movement, ink in the patrices 2 anew, whereby the ink layer is greatly reinforced and the printed copy is completed, and the rollers subsequently are returned to the inking device. Then the lever 16 moves the paper slide 15 fastened to its outer end into the position shown in Fig. 5 by tension action of the spring 51, as at this time the cam disc 50 releases the control arm 48, so that the spring 51 is rendered operative.

As soon as the paper slide assumes its end position and the transparent sheet 13 clamped to the paper frame 12 is inserted between the set line of patrices and the cylinder 9 the latter is lowered for the second time to press the sheet 13 against the patrices 2 and simultaneously transferring the ink present on the printing form 10 to the sheet 13, whereafter the latter sheet is printed on both sides. After the cylinder 9 has been raised again by action of the spring 32, the cam disc 50 forces the paper slide 15 back into position of rest by means of the control arm 48, link 47 and lever 16. During the movement of the paper slide 15 into the printing position, the pawl carrier lever 56 hits the stop 55 and the pawl 54 rocks the ratchet wheel 18 and thereby the gear wheel 52 to the desired extent, so that the transparent sheet 13 is advanced together with the paper carrier frame by the distance between two lines. During raising the printing carriage 21 into inoperative position, the feed lever 17 hits the upper end of the guide loop 41 and the pawl 40 rotationally displaces the cylinder for such an amount about its pivot 39, that an unused portion of the printing form 10 is moved into printing position.

I do not limit myself to the particular size, shape, number or arrangement of parts as shown and described, all of which may be varied without going beyond the scope of my invention as shown, described and claimed.

What I claim is:

1. In a type line composing and printing machine of the type described, in combination, a printing device having a rotatable printing cylinder, means for rotating said cylinder by steps, a resilient printing form mounted on said cylinder, a device for feeding printing paper into printing position under said cylinder between two

successive printing operations of said printing device, a type line setting device, a spacer or justifier device, an inking device correlated to said printing device and adapted for inking in a set type line under said cylinder before two successive printing operations of said cylinder with the rotational adjustment of the latter unaltered, and means for driving said printing device, said printing paper feed device, and said inking device in timed relationship to print a transparent sheet fed to said cylinder on both sides during the second of said successive printing operations by contact of one side directly with the ink still present on the respective type line and of the other side with the part of the ink transferred from said type line onto said printing form during the first of said successive printing operations.

2. In a type line composing and printing machine of the type described, in combination, a printing device having a rotatable printing cylinder, means for rotating said cylinder by steps, a resilient printing form mounted on said cylinder, a device for feeding printing paper into printing position under said cylinder between two successive printing operations of said printing device, a type line setting device, a spacer or justifier device, an inking device correlated to said printing device and adapted for inking in a set type line under said cylinder each time before two successive printing operations of said cylinder with the rotational adjustment of the latter unaltered, and means for driving said printing device, said printing paper feed device, and said inking device in timed relationship to print a transparent sheet fed to said cylinder on both sides during the second of said successive printing operations by contact of one side directly with the respective freshly inked in type line and of the other side with the ink transferred from said type line onto said printing form during the first of said successive printing operations.

3. In a type line composing and printing machine of the type described, in combination, a printing device having a rotatable printing cylinder, means for rotating said cylinder by steps, a resilient printing form mounted on said cylinder, a device for feeding printing paper into printing position under said cylinder between two successive printing operations of said printing device, said printing paper feeding device having a slide for receiving a sheet of paper, rollers carrying said slide for wheeling the same into printing position for said paper sheet, a type line setting device, a spacer or justifier device, an inking device correlated to said printing device for inking in a set type line under said cylinder before two successive printing operations of said cylinder with the rotational adjustment of the latter unaltered, and means for driving said printing device, said printing paper feed device, and said inking device in timed relationship to print a transparent sheet fed to said cylinder on both sides during the second of said successive printing operations by contact of one side directly with the ink still present on the respective type line and of the other side with the part of the ink transferred from said type line onto said printing form during the first of said successive printing operations.

PAUL MARTI.
